ROSCOE HILTON ALDRICH, OF ALLENtown, PENNSYLVANIA, ASSIGNOR TO THE
ALDRICH PUMP COMPANY, OF ALLENtown, PENNSYLVANIA.

METALLIC PACKING.

1,168,144.

Specification of Letters Patent. Patented Jan. 11, 1916.

Application filed April 30, 1915. Serial No. 24,885.

To all whom it may concern:

Be it known that I, Roscoe H. ALDRICH, a citizen of the United States, and a resident of Allentown, in the county of Lehigh and State of Pennsylvania, have invented a new and Improved Metallic Packing, of which the following is a full, clear, and exact description.

My invention relates to metallic packing, and has reference more particularly to a yieldable metallic ring for the packing.

The object of the invention is to provide a simple, inexpensive and efficient metallic packing which is characterized by the provision of a metallic, yieldable ring which carries a resilient member adapted to contract the metallic ring when pressure is applied to said metallic ring.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a section through a pump casing provided with an embodiment of my invention; Fig. 2 is a sectional view through one of the packing rings; Fig. 3 is a similar section through a fragment thereof, showing the same under pressure; Fig. 4 is a plan view of the ring; and Fig. 5 shows means for removing the ring section at the stuffing box.

Before proceeding to a more detailed description of my invention it must be clearly understood that although the metallic packing herein disclosed is designed for use with pump plungers, said packing can be as efficiently utilized for other purposes of similar nature.

Referring to the drawings, 6 represents a ring which is formed of two semi-circular segments 7, the contacting ends of the segments forming a perfect joint. The diameter of the ring so formed is substantially the same as the diameter of the plunger 8 it is to fit. Each of the rings 6 has an exterior, annular groove 9, which is preferably rectangular in cross section, as best seen in Figs. 1 to 3. It has also an interior, annular notch 10, V-shaped in cross section,

which is central with respect to the groove 9 and is in the middle of the ring 6 formed of the two sections. Each end surface of the ring 6 has a central depression 11 resulting in a marginal projection 12 which constitutes the compression lip of the ring, as will appear hereinafter.

Engaging the grooves 9 of the halves 7 of the ring is a rubber ring 13. This rubber ring constitutes the resilient member for the metallic ring and causes the metallic ring to grip the plunger 8 when pressure is applied to the marginal projections 12. The metallic ring being formed of lead or composition is very pliable. Furthermore, due to the provision of the notch 10, said ring is rendered yieldable, that is to say the ring will bend at the notch when pressure is applied to the marginal projections 12. This bending of the ring will cause the inner face of the ring to be slightly curved or bulged as shown in Fig. 3 of the drawing. The pressure on the marginal projections 12 also causes a contraction of the groove 9, compressing the rubber ring 13, which in turn forces the metallic ring against the plunger and continues to force the same until said rubber ring expands to its normal condition. It will be noted that the bending of the ring slightly reduces the internal diameter of the ring at its middle, so that it is made to tightly contact with the plunger.

Pressure to the packing rings 6 can be applied in any suitable way, of which one way is shown in Fig. 1. In this structure a number of superimposed packing rings 6 are provided within a stuffing box 14. The number of packing rings will vary in accordance with the conditions. The lowermost ring engages a bushing 15 with its marginal projection 12; while the uppermost ring 6 engages with its marginal projection a ring 16 which is in turn in engagement with a stuffing gland 17. The successive rings contact with each other through the medium of their marginal projections 12. When pressure is applied to the gland 17 by means of the screws, the same is transmitted to the projections 12. The rings being yieldable will be bent and the rubber ring compressed as before described. These rubber rings abut with their exterior lateral surface against the wall of the stuffing box, and with their interior surface against the rim of the groove of the rings, causing the ring to grip

the plunger 8, as the resistance of the ring is less than that of the material forming the stuffing box. Due to the resilience of the rubber rings the grip action of the metal ring 6 on the plunger 8 is maintained, although the pressure on the marginal projections 12 of the rings 6 is gradually decreasing due to the wear caused by the reciprocation of the plunger within the rings. The notch 10, in addition to creating a point of minimum resistance in the ring sections, serves as a packing groove base, as any lubricant located within said groove 10 will form a packing.

15 While I have described the principle of operation, together with the device which I now consider to be the best embodiment thereof, I desire to have it understood that the device shown is merely illustrative and 20 that such changes may be made as are within the scope of the appended claim.

I claim:

A metallic packing, consisting of a metal-

lic ring rectangular in cross section and formed of two semi-circular sections having 25 square abutting ends, the ring having a straight inner face, a V-shaped notch in said inner face, a rectangular groove in its periphery, a central depression in each side, and an annular rib on each side at the 30 periphery of the ring and bounding the depression, and a rubber ring in the rectangular groove of the ring, whereby when pressure is applied to the ribs of the metallic ring the inner face of said ring will be rendered convex and the rubber ring compressed, thereby causing the metallic ring to tightly contact with the part it surrounds.

In testimony whereof I have signed my name to this specification in the presence of 40 two subscribing witnesses.

ROSCOE HILTON ALDRICH.
